ARTHUR GAUDENZI, OF BADEN, SWITZERLAND, ASSIGNOR TO AKTIENGESELLSCHAFT BROWN BOVERI & CIE, OF BADEN, SWITZERLAND, A JOINT-STOCK COMPANY OF SWITZERLAND

ARC GUIDE FOR METALLIC VAPOR RECTIFIERS

Application filed December 6, 1928, Serial No. 324,181, and in Germany December 19, 1927.

This invention relates to improvements in metallic vapor electric current rectifier apparatus.

In apparatus of the character referred to, it has been proposed heretofore to enclose the anodes within sleeves in order to reduce the possibility of back-firing which may occur when a particular anode is not in operation. Such sleeves have in some constructions been made of insulating material, which was unsatisfactory because of the low mechanical strength of the material and because radiation of heat from the anodes was prevented thereby. Iron sleeves have also been proposed, but were found to be unsatisfactory because of the danger of short-circuiting between the sleeves and the anodes, induced by the occlusion of gases from the sleeve and the collection of positive ions thereabout when the particular anode is out of operation.

Metallic vapor rectifiers of the character described are usually provided with a mercury condensing chamber or dome which, in metal container rectifiers for large outputs, extends into the containers. In rectifiers with a condensation dome extending into the rectifying chamber, the sleeves above mentioned have been omitted and replaced by radially outwardly extending walls which divided the annular anode space between the container wall and the condensation dome into substantially sector shaped cells. These constructions are undesirable because an excessive amount of mercury vapor may collect within the sleeves or within the anode cells, thereby rending the condensation of mercury much more likely in the space closely adjacent the anode and causing back-firing therein and because no provision is made for arc guides which are desirable to maintain the arc in the desired direction.

The undesirable features of the prior construction may be avoided by enclosing the sector shaped anode cells or spaces by a partition separating such spaces or cells from that portion of the container including the cathode. A passageway for mercury vapor between the cathode space and the anode cells is formed by water cooled arc guides

in such partitions which guides prevent entrance of an excessive amount of mercury vapor into the anode cells and maintain the electric arc in the proper direction.

It is, therefore, among the objects of the present invention to provide a rectifier container construction in which the anodes of an electric current rectifier are shut off from the cathode thereof.

A further object of the invention is to provide an electric current rectifier construction in which each of the anodes is separately enclosed.

Another object of the invention is to provide an electric current rectifier construction in which a restricted passage between the cathode chamber thereof and the separate anode chambers prevents entrance of an excessive amount of mercury vapor and serves as an arc guide.

Other objects and advantages will appear to those skilled in the art upon consideration of the following description and the drawings accompanying and forming a part of this specification, and wherein

Figure 1 is a vertical cross sectional view of apparatus embodying the present improvements, and

Fig. 2 is a horizontal cross sectional view, the section being taken on the line A—A in Fig. 2.

Referring to the drawings by characters of reference, 5 indicates a container including side walls, a top plate and a bottom wall. The walls of the container are shown as being water-jacketed to provide for cooling thereof.

A condensation dome 6, also water-jacketed for cooling, extends upwardly and downwardly from the top plate 7 of the rectifier container 5 at approximately the central point thereof. The downwardly extending wall of the condensation dome and the exterior wall of the rectifier chamber form an annular space within which the usual anodes 8 are arranged.

A plurality of walls 9 extend radially outwardly from the downwardly extending wall of the condensation dome and are joined to the side walls of the rectifier container 5. A

wall 11 of substantially annular form extends between the walls of the rectifier container 5 and the downwardly extending wall of the condensation dome, and connects with 5 the radial walls 9.

The sides of the container, the radial walls 9 and the annular wall 11 combine to form a plurality of substantially segment-shaped spaces or cells about the anodes. The wall 10 11 is provided with apertures aligned vertically with respect to the anodes and provided with arc guides 13, which are formed as a double-walled hollow sleeve, and are connected to an inlet conduit 14 and an outlet conduit 16 connected to a suitable source 15 of cooling medium.

The double-walled sleeves or arc guides 13 are set into the openings through partition 11 in a mercury-tight relation so that mercury vapor must pass through the arc guides to enter the anode cells. A portion of the mercury vapor arising from the cathode 12 is condensed before its entrance into the anode cells by the water-cooled arc guides 20 13, so that only relatively small portions of the mercury vapor actually enter these cells. The cells are accordingly under a lower vapor pressure than was the case in constructions proposed heretofore, thus providing for 25 operation of the apparatus with a greater degree of safety. The condensation of mercury vapor on the arc guides 13 may be increased by increasing the surface of the walls of the guides in any well-known manner, such as providing the same with ribs or fins.

Although but one embodiment of the invention has been shown and described, it will be understood that various changes may be made, such as in the size, shape and arrangements of the parts without departing from the spirit of the invention or the scope of the 40 claims.

The invention claimed is:

1. In an electric current rectifier of the metallic vapor type, a container, a hollow wall depending from the top of said container, a horizontal wall connecting with said depending wall, a plurality of radial walls connecting with said depending and said horizontal walls to form a plurality of vapor expansion cells, a plurality of anodes within said container, each of said anodes occupying one of said cells, a vaporizable metallic cathode below said horizontal wall, and double-walled 50 55 arc guides connecting each anode cell with the space occupied by said cathode, said arc guides being adapted to be cooled by a medium flowing therethrough, for condensing vapor passing from the cathode to the anodes.

2. In an electric current rectifier of the metallic vapor type, a container, a condensing chamber having a wall depending vertically into the said container from the top 60 65 wall thereof, a horizontally extending parti-

tion affixed to said wall and to the said container to effect division of the said container into upper and lower chambers, a vaporizable cathode supported within the said lower chamber, a plurality of radially extending 70 walls affixed to the said walls to divide the said upper chamber into a plurality of cells, an anode supported within each of the said cells, a plurality of double walled arc guides affixed to the said partition to constitute restricted 75 passages for the flow of cathode material from the said lower chamber into the said cells, and means for effecting the flow of cooling fluid between the said double walls to effect condensation of vaporized cathode 80 material flowing towards the said cells.

3. In an electric current rectifier of the metallic vapor type, a container, a condensing chamber having a wall depending vertically into the said container from the top wall thereof, a horizontally extending partition affixed to said wall and to the said container to effect the division of the said container into upper and lower chambers, a vaporizable cathode supported within the said lower chamber, a plurality of anodes supported within the said upper chamber, a plurality of spaced double-walled arc guides affixed to the said partition and constituting restricted 90 95 passages for the flow of cathode material from the said lower chamber into the said upper chamber, means for effecting the flow of cooling medium between the said walls of said arc guides to cause condensation of vaporized cathode material flowing from the said lower chamber into the said passages, and a plurality of radially extending partitions affixed to said walls and said horizontally extending partition to form cells about the said anodes and to permit expansion of cathode material flowing through the said guides into the said 100 105 cells.

In testimony whereof I have hereunto subscribed my name this 15th day of November A. D. 1928.

ARTHUR GAUDENZI.
